UNITED STATES PATENT OFFICE

LESTER U. LARKIN, OF ATLANTA, GEORGIA, ASSIGNOR TO LARKIN REFRIGERATING CORPORATION, OF ATLANTA, GEORGIA, A CORPORATION OF GEORGIA

REFRIGERATION SYSTEM

Application filed October 9, 1930. Serial No. 487,542.

This invention relates to refrigeration systems of the dry coil type and has for its object the provision of close automatic control of the admission of refrigerant to the coil, so that at no time shall the refrigerant be admitted to the coil at a rate faster than it can be evaporated, thus ensuring 100% dryness within the coil under all conditions.

Since the evaporative capacity of the coil is dependent upon the rate of heat absorption by the refrigerant within the coil, from the refrigerated chamber, which rate in turn depends upon the initial low temperature of the refrigerant, as well as the temperature of the atmosphere in the refrigerated chamber, it is obvious that since the temperature within the refrigerated chamber itself varies in different locations and from time to time, that no close thermostatic control can be exercised that does not include all of these factors, and that in particular it is not possible to obtain close control by means responsive to the temperature variations in the refrigerated chamber.

However, the temperature variations on the low or effluent side of the refrigeration system are a direct function of the rate of heat absorption into the coil, and variations in the said rate of heat absorption quickly show up in the effluent refrigerant. Consequently, a thermostat inserted in the low or effluent conduit leading from the coil, or in a portion of the coil itself on the low side, is protected from and therefore, unmodified by direct extraneous influences such as the air temperature in the refrigerated chamber, affords a means for quickly adjusting the supply of refrigerant to the demand.

Another object of the invention resides in the specific means for conveniently mounting the temperature responsive element of the thermostat within the refrigerant passage on the low side.

Other objects of the invention will appear as the following description of a preferred and practical embodiment thereof proceeds.

In the drawing in which the same characters of reference have been employed throughout the several figures to designate the several parts:

Figure 1 is a view in elevation showing a fragment of the evaporator coil in a "dry" coil refrigeration system including the control valve and the thermostatic unit included in the present invention;

Figure 2 is a longitudinal section through the final portion of the coil pipe showing the fitting, by means of which the thermostatic element may be intercalated in the low side of the system;

Figure 3 is a longitudinal section showing the same type of fitting, but arranged so that the thermostatic element is in the effluent conduit beyond the coil;

Figure 4 is a perspective view showing a portion of the thermostatic element and the split plug by means of which it is secured in the fitting; and

Figure 5 is a perspective view of the halves of the split plug.

Referring now in detail to the several figures, the numeral 1 represents in general the coil of a refrigeration system of the dry coil type, such as is described and claimed in my copending application, Serial No. 422,364, filed January 21, 1930. Refrigerant in liquefied form is supplied from a condenser, not shown, by way of the conduit 2 to the control valve 3. Said valve marks the head of the column of liquid refrigerant in the system, and refrigerant is permitted to escape by way of the conduit 4 into the coil 1, it being the purpose of the invention to so control the escape of the refrigerant that it will be supplied only in proportion to the expansion capacity of the coil so that it shall be evaporated into a gas by the time it enters said coil to ensure that the coil shall be dry throughout without containing any refrigerant in liquid state. This implies a close control of the valve 3, which control is accomplished by means of a thermostatic element including a hollow bulb 5 and a diaphragm chamber 6 connected by a tube 7, the common chamber thus formed containing a volatile liquid such for instance, as ether. The diaphragm wall of the diaphragm chamber 6, which is not shown, controls a valve stem

also not shown.

The evaporative capacity of the coil 1

varies according to the rate of heat exchange at any moment between the walls of said coil and the atmosphere in the refrigerated chamber. This rate of heat exchange in turn, 5 varies with changes in temperature of the atmosphere in the refrigerated chamber, and it is also determined by the inition temperature of the refrigerant as well. There is only one element in a refrigeration system which 10 responds directly and quickly to all of these factors, namely the refrigerant in the final portion of the coil conduit or in the adjacent portion of the effluent conduit leading from said coil. It is old to attempt to control a 15 valve by a thermostatic element responsive to the temperature of the refrigerated chamber, but since the evaporative capacity of the coil is only sluggishly responsive to variations in temperature of the refrigerated chamber, 20 a control of the valve 3 based upon this datum is not close enough to avoid at times, the introduction of refrigerant in liquid state into the coil, and at other times the admission of insufficient refrigerant to operate the coil up 25 to its capacity. However, since the temperature of the effluent refrigerant in the final end of the coil or in the adjacent conduit leading back to the compressor is at an immediate index of the evaporative capacity of the 30 coil, a thermostatic element placed within the conduit at this region so as to be affected solely by the temperature of the effluent refrigerant, unmodified by any extraneous temperature variations, is capable of imparting an 35 exact, immediate and close control to the valve 3.

With this object in view, I have devised means for the convenient insertion of the bulb 5 in the final end of the coil 1, or selectively, 40 in the adjacent end of the conduit leading from said coil to the low side of the compressor. This means comprises a pipe fitting 8, generally in the form of a T having a through bore 9 and a branch nipple 10. One 45 end of the fitting is counter-bored as indicated at 11, to form a shoulder 12 and the tube 7 of the thermostatic element is provided with a plug or collar 13 adapted to seat in said counter-bore against the shoulder 12 50 and to be suitably sealed therein, as for instance by sweating with solder. Since the thermostatic element including the dia- 55 phragm chamber, bulb and the connecting tube comes as an assembled unit with the volatile liquid enclosed, it is obvious that heat cannot safely be applied either to the bulb or diaphragm chamber on account of risk of bursting the thermostatic element. Consequently, the plug 13 is preferably 60 formed in halves 14 and 15 as indicated in Figure 5, which halves are fitted about the tube 7 at some point intermediate the dia- phragm chamber and bulb, and the halves are then sweated or otherwise secured to said tube in fluid-tight relation. The bulb to-

gether with the portion of the tube 7 lying between the bulb and plug 13 is then introduced into the through-bore of the fitting 8, until the plug 13 seats upon the shoulder 12. The assembled fitting and thermostatic element thus forms a unit which can be positioned either as shown in Figure 2 with the bulb inserted in the final end of the coil, or it can be positioned as shown in Figure 3 with the bulb in the eduction pipe. In either 70 instance, the bulb 5 is preferably spaced from the walls of the surrounding conduit so as to be altogether enveloped by the effluent refrigerant. The fact that the tube 7 is bendable makes it possible readily to adjust the 75 5 so as to place it in the correct position.

The thermostatic element including the diaphragm chamber, bulb and connecting tube, with the assembled plug or collar may be 80 sold as an article of manufacture, or it may be supplied in combination with the fitting. While the plug 13 is designed eventually to be 85 soldered or sweated into the fitting so as to prevent being blown out by pressure in the system, yet it may be supplied to the purchaser, unsecured in the fitting with the design 90 that the purchaser shall solder it in himself.

It is obvious that the invention should not be limited in scope to the specific form of 95 pipe fitting herein shown or to specific construction of thermostatic element and consequently, it is to be understood that variations in the construction of either of these features is within the purview of the protection afforded by the appended claim. 100

What I claim is:

In combination, pipe fitting adapted to be intercalated in the conduit on the low side of a refrigeration system for the purpose of introducing a thermostat directly into the stream of effluent refrigerant in said system, comprising a T having a through-bore and a branch nipple, one end of said through-bore being counter-bored, and a thermostatic element comprising a bulb and a tube connected thereto, said tube passing axially within said through-bore, and means secured to said tube and adapted to be secured in sealing relation in the counter-bored end 110 of said T. 115

In testimony whereof I affix my signature.
LESTER U. LARKIN.
